UNITED STATES PATENT OFFICE.

FREDERICK HODDICK, OF BUFFALO, NEW YORK, ASSIGNOR TO GEORGE A. PRINCE & CO., OF SAME PLACE.

IMPROVEMENT IN MELODEONS.

Specification forming part of Letters Patent No. 59,128, dated October 33, 1866.

To all whom it may concern:

Be it known that I, FREDERICK HODDICK, of the city of Buffalo, county of Erie, and State of New York, (assignor to GEORGE A. PRINCE, CHAS. E. BACON, and CALVIN F. S. THOMAS,) have invented a certain new and useful Improvement in Melodeons or other Reed Musical Instruments; and I do hereby declare that the following is a full and exact description thereof, reference being had to the accompanying drawings, making a part of this specification, in which—

Figure I is a vertical section, Fig. II is a rear-end view, Fig. III is a top-plan view, and Fig. IV a detail view, of a portion of the tremolo-bellows, showing the principle of the operating parts of my improvement.

The nature of this invention relates, first, to devising and constructing a tremolo-bellows having an inlet and outlet valve for the purpose of operating a tremolo in musical instruments; second, a tremolo-bellows, or its equivalent, placed and used in connection with the wind-chest and swell-valve of reed musical instruments in such manner that the tremolo-bellows will act upon the swell-valve to produce the effects of a tremolo.

Letters of like name and kind refer to like parts in each of the figures.

A represents the frame-work or body of a melodeon or other reed musical instrument, and B the keys thereof. C represents the wind-chest, and D the reed-chamber. E represents the swell, which consists of a hinged valve, located in the rear of the reed-chamber, and when closed forms the back of the reed-chamber. All of these parts are and may be of common construction.

My improved tremolo-bellows is represented at F. It has two valves, f^1 and f^2 , which are supported upon two arms, g^2 g^3 , which arms are connected with and project from the crank-shaft G. These valves open and close in opposite directions, and alternately. The one closes as the other opens, and vice versa.

The valve f^1 connects with the open air and opens inwardly, and the valve f^2 forms a connection with the wind-chest by means of the aperture f^3 and opens outwardly. These

valves, and also the valve-seats, may be made of leather or other suitable material in a common manner.

Upon the crank G' of the valve-shaft G is represented a ring or grooved wheel, H, which is made of leather or other suitable material, and at I is represented a fine wire spring, the coil part of which is connected with a pin, which is fastened and projects from the hinged and movable flap J of the bellows, and the free end of this wire spring is extended horizontally and acts upon the wheel H. This part is bent in a peculiar form, and adapted by its peculiar form, as it moves over the wheel, thereby to move the crank-shaft in such manner as to open and close the valves.

When the flap of the bellows is open the valve f^1 is closed and valve f^2 is open. Now, as the flap closes this wire spring acts upon the wheel H, and through that upon the crank G', shaft G, and valve-arms g^2 g^3 in a manner to open the valve f^1 and close the valve f^2 , and as the flap opens the reverse effect is produced, and so alternately.

The wire spring K is connected with the flap in a manner to open it, and the wire spring L is also connected with the flap near the back end thereof, and passes over the front end, and forms a connection with the connecting-rod M, and the connecting-rod M also connects with the swell-valve E, as shown at m', Fig. III.

Now, the operation is as follows: The air is exhausted through the outlet-valve f^2 by the suction or exhaust action of the wind-bellows of the instrument, which exhaust movement has the effect to close the flap of the tremolo-bellows, and thereby, through the mechanism before described, open the inlet-valve f^1 and allow the external air to rush in and fill the tremolo-bellows, at the same time closing the outlet-valve f^2 , and thus the air is made to act in and upon the tremolo-bellows like steam upon and in a steam-engine. A rapid movement of the valves and the flap is thereby effected, and as the flap is connected with the swell-valve of the instrument, as before described, a rapid tremulous movement is communicated to the swell-valve, which has all the effect upon the vibrations of the air and musical sounds which

is produced by tremolo attachments, which are specifically constructed at considerable expense and attached to such instruments.

At N is shown a clamping-finger, hinged at n' , and connected with the rod O, so that by moving the rod in one direction the clamping-finger is pressed down upon the tremolo bellows to hold it closed; and when thus closed the rod M is disconnected, and then the swell and all other parts of the instrument may be used in the same manner and with like effect as if the tremolo-bellows were not connected with the instrument.

What I claim as my invention, and desire to secure by Letters Patent, is—

1. A tremolo-bellows, F, having inlet and outlet valves $f^1 f^2$, constructed and operating substantially as herein described.

2. A tremolo-bellows, F, or its equivalent, placed and used in connection and combination with the wind-chest and swell-valve of reed musical instruments, for the purpose and substantially as described.

FREDERICK HODDICK.
